UNITED STATES PATENT OFFICE.

INGEMAR K. RYSTEDT, OF DAYTON, OHIO, ASSIGNOR, BY DIRECT AND MESNE ASSIGNMENTS, TO THE RYSTEDT-ENGINEERING COMPANY, OF DAYTON, OHIO, A CORPORATION OF OHIO.

DESIGN FOR A GAME FIGURE.

Application filed June 19, 1922. Serial No. 2,737. Term of patent 3½ years.

To all whom it may concern:

Be it known that I, INGEMAR K. RYSTEDT, a citizen of the United States of America, residing at Dayton, in the county of Montgomery and State of Ohio, have invented a new, original, and ornamental Design for a Game Figure, of which the following is a specification, reference being had to the accompanying drawings, forming part thereof.

In the drawing the figure is a perspective view illustrating a game figure of my improved design.

I claim:

The ornamental design for a game figure as shown.

INGEMAR K. RYSTEDT.
